(57) **CLAIM**

The ornamental design for a horse feed bag, as shown and described.

DESCRIPTION

FIG. 1 is a perspective view of a horse feed bag showing our new design.

FIG. 2 is a left side elevation view thereof.

FIG. 3 is a right side elevation view thereof.

FIG. 4 is a top plan view thereof.

FIG. 5 is a bottom plan view thereof.

FIG. 6 is a front elevation view thereof.

FIG. 7 is a rear elevation view thereof; and,

FIG. 8 is a perspective view of a horse feed bag, shown in a condition of use for clarity of disclosure.
The broken lines in the drawings depict portions of the horse feed bag that form no part of the claimed design.
The drawings are shaded to indicate contrasting surfaces.

1 Claim, 5 Drawing Sheets
